UNITED STATES PATENT OFFICE.

CHARLES A. GILLINGHAM, OF LAKEWOOD, OHIO, ASSIGNOR TO NATIONAL CARBON COMPANY, OF CLEVELAND, OHIO, A CORPORATION OF NEW JERSEY.

DESIGN FOR AN ELECTRIC-BATTERY CASING.

46,023.

Specification for Design.

Patented June 30, 1914.

Application filed March 16, 1914. Serial No. 825,181. Term of patent 14 years.

To all whom it may concern:

Be it known that I, CHARLES A. GILLINGHAM, a citizen of the United States, residing at Lakewood, in the county of Cuyahoga and State of Ohio, have invented a new, original, and ornamental Design for an Electric-Battery Casing, of which the following is a specification, reference being had to the accompanying drawing, forming a part thereof.

The figure of the drawing shows the battery casing in perspective.

I claim:

The ornamental design for an electric battery casing as shown.

CHARLES A. GILLINGHAM.

Witnesses:

WALLACE W. MANN,
LEE CARROLL HAWLEY.
